EDWARD H. CURETON AND JOHN E. ULRICH, OF RICHMOND, INDIANA, ASSIGNEES TO THE AMERICAN SEEDING MACHINE COMPANY, OF SPRINGFIELD, OHIO, AND RICHMOND, INDIANA, A CORPORATION OF OHIO.

SINGLE-DISK FURROW-OPENER.

1,189,066.

Specification of Letters Patent. Patented June 27, 1916.

Application filed March 10, 1916. Serial No. 83,810.

To all whom it may concern:

Be it known that we, EDWARD H. CURETON and JOHN E. ULRICH, citizens of the United States, residing at Richmond, in the county 5 of Wayne and State of Indiana, have invented certain new and useful Improvements in Single-Disk Furrow-Openers, of which the following is a specification.

This invention relates to improvements in 10 single disk furrow openers, and more particularly relates to a furrow opener of the type in which an arch is employed for supporting the boot and its attached toe scraper.

An object of the invention is to provide 15 a construction whereby the toe scraper may be maintained in proper contact with the convex side of the disk.

A further and more specific object of the 20 invention is to provide a supporting arch so constructed that it will have the necessary and proper amount of resiliency and torsional spring for maintaining the toe scraper in yielding contact with the disk and in proper relation therewith throughout 25 the entire length of the scraper.

In the accompanying drawings:—Figure 1 is a side elevation of a furrow opener embodying the improvements, looking at the 30 concave side of the disk. Fig. 2 is also a side elevation looking at the convex side of the disk. Fig. 3 is a perspective view of the arch.

In the construction of furrow openers of 35 the type referred to, difficulty has been encountered in maintaining the toe scraper which is attached to the lower end of the boot in proper relation with the disk due to irregularities in manufacture which are almost universally found in curved disks, 40 as a result of which there are some points at which the pressure of the toe scraper is not sufficient to properly clean the disk, or there are some points at which the pressure is greater than necessary, thereby causing 45 not only unnecessary draft but wear on the toe scraper, and, in some cases, as in loose soil, locking the disk against revolution. These difficulties are encountered where the arch is made of malleable iron or bar steel, 50 which are too rigid, although attempts have been made in the bar steel form of arch to provide some resiliency to obviate these difficulties. However, with an arch of bar

steel of sufficient rigidity to properly perform its supporting function when pressure 55 is transmitted to the disk through the arch as is usually the case, the difficulty is not overcome, because of the failure of such arches to yield in a torsional direction which is necessary for properly maintaining the 60 scraper against the disk throughout all portions of its length. Another difficulty with the bar steel arch of resilient character is that it has been found impracticable to follow out the desirable and conventional form 65 of attaching the boot thereto; that is, attaching it to the rear end of the arch near the upper end of the boot and then employing the lower end of the boot for the attachment of the scraper, as the bar steel 70 arch does not provide sufficient rigidity for this purpose, making it necessary to continue the arch down to the lower end of the boot. To overcome these difficulties we have devised the following construction: 75

Referring to the drawings, 1 represents the drag-bar; 2 a concavo-convex disk of the usual form revolvably connected thereto; 3 an arch embodying our improved construction, the forward end of which is connected to the drag bar 1 and the rear end of which has connected thereto a boot 4; 5 a toe scraper connected to the lower end of the boot projecting toward the center of the disk and having its scraping edge shaped 80 to conform to the convex side of the disk; 6 a scraper for the concave side of the disk connected to the arch; and 7 a raising and lowering rod connected to the arch; all of these parts, with the exception of the peculiar construction of the arch, being of the 85 usual form.

As shown in Figs. 1 and 3, the arch is of channel form the forward end 3^a being enlarged somewhat to form a point of attachment for the drag-bar and the rear end 3^b being flattened to provide a point of attachment for the boot. This arch is constructed of pressed steel, so that it can be made comparatively light and resilient in character, 95 the channel form, however, providing the necessary rigidity to enable it to perform its supporting function but at the same time resilient enough that, the parts being properly adjusted, it will hold the scraper 100 yieldably against the side of the disk. 105

- Further, owing to its peculiar character the arch will yield under torsional strain, which is very beneficial in maintaining the scraper in proper relation to the disk, but, as before 5 stated, owing to irregularities in the manufacture of disks, and, also, to wear in the bearings thereof, the scraper, in order to press evenly against the disk throughout its entire length, must constantly change its 10 position relative to the line of travel; that is, the line of curvature of the disk as it passes the scraper, may constantly change, causing a lateral movement of the scraper, which exerts a torsional strain on the arch. 15 If the arch is too rigid, as in the case of the malleable or bar steel types, this will have the effect of causing one portion of the scraper to leave the side of the disk, whereas in our construction, the peculiar form of 20 arch permits it to yield to torsional strains, allowing the scraper to bear against the disk throughout its entire length so as to properly perform its scraping function and also to yield when necessary, so as not to 25 exert too great pressure upon the disk, thereby eliminating unnecessary draft, wear on the scraper and locking of the disk. This construction of arch also permits the boot to be attached thereto in the most desirable 30 and conventional way; that is, at a point near the upper end of the boot, the toe

scraper being secured to the lower end of the boot as is usual and desirable.

Having thus described our invention, we 35 claim:

1. In a disk furrow opener, a support, a curved disk revolvably mounted on said support, an arch connected with said support and extending over said disk, a boot rigidly connected with said arch near the upper end 40 of said boot, and a toe scraper connected to the lower end of said boot lying against said disk, said arch being constructed to hold said scraper in yielding contact with the disk and to be capable of yielding to torsional strains substantially throughout its length. 45

2. In a disk furrow opener, a support, a curved disk revolvably mounted on said support, a resilient pressed-steel channel-shaped arch connected to said support and extending over said disk, a boot connected to the rear end of said arch, and a toe scraper for said disk connected to the lower 50 end of said boot. 55

In testimony whereof, we have hereunto set our hands this 2nd day of March, 1916.

EDWARD H. CURETON.
